[57] CLAIM

The ornamental design for a cabinet for electronic equipment, as shown and described.

DESCRIPTION

FIG. 1 is a perspective view of a cabinet for electronic equipment, showing our new design;

FIG. 2 is an elevational view of the lefthand side, which is symmetrical with respect to the righthand side;

FIG. 3 is a front elevational view which is identical to the rear elevational view;

FIG. 4 is a top plan view; and,

FIG. 5 is a bottom plan view thereof.
